Primary Examiner — Sandra S Snapp*Assistant Examiner* — Ieisha N Price(74) *Attorney, Agent, or Firm* — Jordan Meggison-Decker; BrownWinick Law Firm(57) **CLAIM**

The ornamental design for a coulter blade, as shown and described.

DESCRIPTION

FIG. 1 is a perspective view of an coulter blade showing my new design;

FIG. 2 is a front elevational view thereof;

FIG. 3 is a rear elevational view thereof; and,

FIG. 4 is a right side elevational view thereof.

The broken lines in the drawings illustrate portions of the coulter blade and form no part of the claimed design.
